US00D624065S

(12) **United States Design Patent**
Bosch et al.

(10) **Patent No.:** **US D624,065 S**
(b4) **Date of Patent:** **** Sep. 21, 2010**

(54) **CASE FOR ELECTRONIC DEVICE**

(76) Inventors: **John P. Bosch**, 7835 E. McClain Dr., #103, Scottsdale, AZ (US) 85260; **J. Ryan Bosch**, 7835 E. McClain Dr., #103, Scottsdale, AZ (US) 85260

(**) Term: **14 Years**

(21) Appl. No.: **29/355,604**

(22) Filed: **Feb. 10, 2010**

(51) **LOC (9) Cl.** **14-03**

(52) **U.S. Cl.** **D14/250**

(58) **Field of Classification Search** **D14/140, D14/142, 167, 217, 218, 240, 242, 248, 250–253, D14/299, 341–347, 440; D3/200–201, 215, D3/218–219, 226, 228, 269, 301, 272–273, D3/276, 294; D13/103, 107–108, 119; 220/4.02; 224/191, 240, 241, 245, 682–683; 248/206.2–206.4, 248/220.21, 279.1, 309.1; 361/679.3, 679.56; 379/420.04, 426, 433.11, 446–447, 454, 379/455; 455/575.1, 575.6, 575.7, 575.8, 455/575.9; 190/100; 206/305, 320**

(57) **CLAIM**

The ornamental design for a case for electronic device, as shown and described.

DESCRIPTION

FIG. 1 is a front perspective view of a case for electronic device, showing our new design;

FIG. 2 is a front elevational view thereof;

FIG. 3 is a right side elevational view thereof;

FIG. 4 is a top view thereof (and also a mirror image of the bottom);

FIG. 5 is a rear elevational view thereof; and,

FIG. 6 is a left side elevational view thereof.
